UNITED STATES PATENT OFFICE.

CHARLES S. JENNINGS, OF NEW HAVEN, CONNECTICUT, ASSIGNOR TO
THOMAS KENNEDY AND CHARLES BLIVEN, OF NEW YORK, N. Y.

IMPROVEMENT IN THUMB-LATCHES.

Specification forming part of Letters Patent No. 178,933, dated June 20, 1876; application filed May 6, 1876.

To all whom it may concern:

Be it known that I, CHARLES S. JENNINGS, of New Haven, in the county of New Haven and State of Connecticut, have invented an Improvement in Thumb - Latches; and I do hereby declare the following, when taken in connection with the accompanying drawings and the letters of reference marked thereon, to be a full, clear, and exact description of the same, and which said drawings constitute part of this specification, and represent, in—

Figure 1, a front view; Fig. 2, a transverse section; Fig. 3, a vertical central section; Fig. 4, a transverse section through the case on line *zz*, showing the rear end of the latch-bolt; and in Fig. 5, a perspective view of the latch-bolt.

This invention relates to an improvement in that class of thumb-latches which are constructed with transverse sliding bolts, and known to the trade as "store - door latches," the object of the invention being to produce a right - angular lever action directly upon the bolt; also, to adapt the handle to a right or left latch, and, also, to draw the latch - bolt without an unusual movement of the thumb-piece; and the invention consists, first, in combining in a latch - handle the vertically-moving thumb-lever, with a second lever moving transversely and in connection with the latch-bolt, so that the downward movement of the thumb - piece imparts through the second lever a direct transverse movement; second, in providing the handle-plate with a fulcrum upon each side of the thumb-lever for the said second or transverse lever, whereby the said second lever may be adjusted for either side of the door, or right and left hand latch; third, in constructing the tail of the bolt with a bearing for the actuating lever upon the opposite side of the case from which the lever enters.

A is the handle-plate, provided with a handle, *B*, in the usual manner. In this plate the thumb-piece *C* is hung upon a pintle, *a*, also in the usual manner. From the pintle the thumb-piece extends down, forming an arm, *D*, of the thumb-lever.

On the back of the handle-plate a bell-crank lever, *E F*, is hung upon a fulcrum, *d*, this

fulcrum being at right angles or vertical to the horizontal pivot *a* of the thumb-lever, and so that, by depressing the thumb-piece, as indicated in broken lines, the arm *F* of the bell-crank or transverse lever will be thrown back, as indicated in broken lines, Fig. 2. In order that this lever *E F* may be set for either side of the door, or for a right or left hand door, a similar fulcrum, *d'*, is arranged upon the opposite side of the thumb - lever *C D*, and the lever *E F* is constructed so as to be changed and set upon either fulcrum, according to the position required.

The lever *E F* enters through the latch-case, or in connection with the latch - bolt, so that its transverse movement, when thrown back by the thumb - lever, will draw in the latch - bolt, and this is applicable to various known constructions of latches.

It will be readily seen that the farther the bearing for the lever *E F* on the latch-bolt is carried to the opposite side of the latch-case, the less may be the movement of the thumb-piece. To do this I construct the case *G* with a recess at its rear end, and make the bolt broader at its rear end, as at *e*, so as to come substantially flush with the outside of the case, as seen in Figs. 2, 3, and 4, and in each of these extensions of the latch-bolt, and upon the side opposite where the lever strikes, a bearing, *f*, is made for that lever, hence the lever is enabled to take its bearing at the extreme opposite side of the case, and thus enable the movement of the latch - bolt without an unusual movement of the thumb - lever, and with much less friction upon the latch-bolt, because the sliding movement of the lever will be less as the distance of the bearing from the fulcrum is increased.

Corresponding handles may be placed upon opposite sides of the door, and each lever will take its bearing upon its own independent seat, and upon the side of the case opposite that in which the lever enters.

In the arrangement of the handle upon the opposite side, it will be understood that the transverse lever *E F* must be changed to the other fulcrum.

I claim—

1. The combination, in a latch - handle, of the thumb - lever C D, and transverse lever E F, substantially as described.
2. The combination, in a latch - handle, of the thumb - lever C D, the transverse lever E F, and a fulcrum at each side of the thumb-lever for the adjustment of the transverse lever, substantially as described.
3. In a sliding thumb - latch, the bolt, con-

structed with a transverse projection, *e*, through the case at the rear end, so as to form bearing *f* for the latch-lever, substantially as described.

C. S. JENNINGS.
